(57) **CLAIM**

The ornamental design for toy figure as shown and described.

DESCRIPTION

1.1 : Perspective

1.2 : Front

1.3 : Back

1.4 : Left

1.5 : Right

1.6 : Top

1.7 : Bottom

Reproduction **1.1** is a perspective view of a toy figure showing our new design; reproduction **1.2** is a front elevation view thereof; reproduction **1.3** is a rear elevation view thereof; reproduction **1.4** is a left side elevation view thereof; reproduction **1.5** is a right side elevation view thereof; reproduction **1.6** is a top plan view thereof; reproduction **1.7** is a bottom plan view thereof.

The stipple shading shown throughout the drawings represents a contrast in appearance.

(Continued)

The broken line showing of the toy figures is for the purpose of illustrating portions of the article that forms no part of the claimed design.

1 Claim, 7 Drawing Sheets
